UNITED STATES PATENT OFFICE.

WILLIAM PAINTER, OF BALTIMORE, MARYLAND, ASSIGNOR OF ONE-HALF
TO LEWIS R. KEIZER, OF SAME PLACE.

AUTOMATIC MAGNETO-SIGNAL FOR TELEPHONES.

SPECIFICATION forming part of Letters Patent No. 269,225, dated December 19, 1882.

Application filed March 2, 1882. (No model.)

To all whom it may concern:

Be it known that I, WILLIAM PAINTER, of Baltimore city, State of Maryland, have invented certain new and useful Improvements 5 in Automatic Magneto Signaling Apparatus for Telephones; and I hereby declare the same to be fully, clearly, and exactly described as follows, reference being had to the accompanying drawings, in which—

- 10 Figures 1 and 2 are end elevations, and Fig. 3 is a side elevation, of a magneto-instrument of the crank form embodying my present invention. Fig. 4 is a similar view of a detail of construction. Fig. 5 is a sectional view of the 15 crank-shaft on the line $x-x$ of Fig. 3. Fig. 6 is an elevation partly in section of a push-button apparatus, and Fig. 7 a similar view of another modification embodying the same invention.
- 20 My said invention relates to magneto-call instruments for telephone-lines; and it consists, first, in so combining therewith a telephone-supporting device and certain operative mechanism that in the act of replacing the telephone on its support, or incidental thereto, a 25 step is necessarily involved which shall result in the generation of a magneto impulse that signals the central office that the user is done with the line, said signaling being automatic 30 in the sense that it involves no volition to that end on the part of the user; second, in an automatic switch for shunting the coil of the armature out of circuit when the instrument is in its normal condition, and into circuit when a 35 call is being made or the automatic signaling impulse is being transmitted.

In operating telephone-exchanges it is desirable that prompt notice be given when the user is done with the line, in order that it may 40 be immediately placed at the disposal of another person and the various connections restored to their normal condition. This has been attempted in the class of signals to which my invention relates by instructing subscribers 45 to signal the central office or exchange when they are through using the line either by turning the crank or pressing the button of the magneto-call; but such action on the part of subscribers cannot practically be enforced. The 50 signaling of the exchange can be accomplished

successfully in two ways—either automatically, in the sense that an act normal and usual in replacing the instrument shall actuate the signal, or else by necessitating a step preliminary or incidental thereto which shall have the same 55 effect. By the use of such means the necessity for cutting in by the office on connected lines to ascertain if the conversation is completed is avoided, the business of the exchange is facilitated, time and labor are saved, and subscribers are spared the annoyance of frequent 60 interruptions while conversing.

My invention is applicable to either the crank or push-button form of magneto-call instruments, and by its use the exchange is automatically signaled when the subscriber is done using the line. This is accomplished, broadly speaking, by causing the telephone, as it is replaced, to actuate the generator, and thereby produce the necessary magneto impulse to ring 70 a bell or drop a signal at the exchange. Specifically it is done either by causing the act of hanging up the telephone (or an act necessarily preliminary thereto) to release a reserve force generated in the act of first signaling the office, which force serves to actuate the magneto-call, or by necessitating an act on the part of the user preliminary to hanging up the telephone which shall produce the desired magneto-signal, or, finally, by causing the direct 75 weight of the telephone to act upon the armature of the magneto-call in such manner as to impart to it the sudden movement necessary to generate the signaling impulse. In the accompanying drawings I have shown an example of each of these three forms. In the first the turning of the crank in calling the office or in answering its call stores a reserve force by expanding a spring, which force is automatically released by the descent of the telephone-hook as the instrument is hung up, and the signal is given by such release. In the second the telephone-hook is closed by a bolt or latch, which must be retracted before the telephone can be hung up, and the act of re- 80 tracting the bolt is made to produce the magneto-signal. In the third the descent of the hook by the direct weight of the telephone retracts the armature and sends the signal. Modifications of these forms of apparatus are 85 90 95 100

obvious, and I do not limit myself to the use of the precise devices shown.

Referring now to the accompanying drawings, in which what I deem the best embodiments of the three forms of device are shown, 5 A A represent the usual U-shaped magnets, secured in the call-box, and *a* is the shaft to which is attached the crank *a'*. On the shaft *a* is a gear-wheel, *b*, that meshes with a smaller wheel, *K*, on the shaft *h*, which latter carries the usual revolving armature, *H*, and coil or helix. A spring, *l'*, which is attached to the connection *m'*, is in contact with the end of the shaft *h*, as usual. The shaft *a* is mounted in bearings 10 *c' c'*, and carries at its extremity a toothed wheel, *C*.

B is a disk having a radial lug, *c*, and this disk is secured to or integral with a sleeve, *J*, which is mounted on the shaft *a*, and is free 15 to revolve in the bearing *c'*.

E is a spring secured at one end to a stud, *e*, on the disk *B*, and at the other to a stud, *e'*, on the frame of the magnets. On the stud *e* is pivoted a pawl, *F*, adapted to engage with 20 the wheel *C*, and having a lug, *f'*, which projects through a hole, *G*, in the disk *B*. A spring, *g*, on the inner side of the disk presses on the lug *f'* and holds the pawl *F* normally in engagement with the wheel *C*, as shown in Fig. 25 1. A lug, *f*, on the bearing *c'* serves to lift the lug *f'*, disengaging the pawl from the wheel *C*. (See Fig. 2.)

The inner end of the sleeve *J* is cut away or flattened at *j*, Figs. 3 and 5, and *l* is a contact-spring having a connection, *m*, for completing the circuit through the armature-coil. When the apparatus is in its normal position, Fig. 1, the flattened portion of the sleeve *J* is immediately under the spring, as shown in Fig. 5, 30 and the parts are not in contact, the spring *l* in this position resting against the contact-bar *l''*, which is in electric connection with the line at *m'*, whereby the armature-coil is cut out. As soon as the sleeve *J* turns so as to bring 35 its cylindrical surface under the spring *l*, as in Figs. 2 and 3, the latter is lifted clear of the bar *l''*, and the armature-coil is thrown into circuit by contact of the spring *l* with the sleeve *J*, said sleeve being in electric connection with 40 the frame of the magnets and with the armature-shaft, to which one end of the coil is attached, as usual. The other end of the coil is in electric connection with the spring *l'* through the pin *h*, also in the usual way. It will be seen 45 that I avail myself of the two definite positions of the sleeve to secure the necessary electrical connection without resort to special automatic shunt mechanism, such as heretofore employed in connection with the armature-coil.

50 *D* is the telephone hook or support, pivoted in the side of the box, and having the usual spring by which it is thrown into the position shown in dotted lines, Fig. 4 when the telephone is removed. It is provided with an 55 arm, *D'*, having two ribs, *d d'*, on its inner side, adapted to arrest the revolution of the disk *B* by engaging with its radial lug *c*. These

ribs are curved in the arcs of circles described about the pivot of the hook or support.

Fig. 1 illustrates the normal position of the 70 disk, pawl, and spring, and Figs. 2 and 3 the position of these parts while the instrument is in use or after a call has been made.

In operation as the crank *a'* is turned the 75 armature *H* is revolved and the signal is sent to the office. Incidentally, the toothed wheel *C* revolves, carrying with it the disk *B* by reason

of the engagement of the pawl *F* with the wheel, and at the same time expanding the 80 spring *E*. When the disk has turned nearly 85 to the position shown in Fig. 2 the lug *f'*, attached to the pawl *F*, encounters the lug *f*, and the pawl is lifted out of engagement with the wheel *C*, which thereafter revolves independently of the disk pending the sending of the 90 signal. The line of traction of the spring *E* now being to the left, Fig. 2, of the shaft *a*, it

tends to cause the disk *B* to revolve in the direction of the arrow; but this is prevented by reason of the engagement of the lug *c* with 95 the rib *d'* of the telephone-hook, and the spring is therefore held under tension.

When the signal is answered by the exchange or central office the subscriber takes down the telephone 100 to use it, and the hook tilts to the position shown in dotted lines, Fig. 4, causing the rib *d'* to pass clear of the lug *c*. The disk *B* thereupon moves slightly forward until the lug *c* strikes the upper rib, *d*, which by the tilting of 105 the hook has been brought over the lug *c*, the lug *f'* still remaining upon *f* and continuing to hold the pawl *F* out of engagement with the wheel *C*.

When the subscriber has finished using the line and hangs up the telephone the hook 110 *D* and arm *D'* are again tilted into the position shown in full lines, Fig. 4, and the lug *c* passes between the ribs *d d'* and is released.

The spring *E* is now free to act, and it effects a half-turn of the disk *B*, which carries with 115 it the wheel *C*, by reason of the engagement 120 of the pawl *F* with the latter. This engagement occurs as soon as the lug *f'* on the pawl passes clear of the lug *f*. The armature *H* is thus caused to revolve, generating the mag- 125

neto impulse to actuate the signal at the of- 130 fice, giving notice that the subscriber has hung up the telephone.

In Fig. 6 is shown a form of device embodying my invention, belonging to the second class hereinbefore referred to. In this case I inter- 130 pose an obstacle to hanging up the telephone of such nature that the signal is a necessary

preliminary to replacing the instrument on the hook or other support. *A* is the magnet, *n* the helix, and *N* the armature. The latter is 135 attached to a lever, *O*, pivoted at *o*, and is of the usual form. *P* is the push-button, attached to a rod, *p'*, which carries an arm, *Q*. The inner end of the rod *p'* bears upon the lever *O*, as shown.

R is the telephone-hook, the end of which is covered normally by a sliding bolt, *p*, attached at *r* to the arm *Q*. In the position shown the telephone is supposed to be in use. Before it

can be hung up the bolt *p* must be retracted by pressing upon the push-button; but in doing so the armature is withdrawn from the magnet, and the signal is thereby sent to the office. I have shown the hook *R* in Fig. 6 as pivoted and having a spring for lifting it, because this is the conventional form, and I have illustrated my invention as applied thereto as a simple addition. The pivoting therefore is merely incidental.

Fig. 7 illustrates the third form of device embodying my invention. In this case the weight of the instrument is relied upon to send the signal as the telephone is hung up. The magnet *A*, helix *n*, armature *N*, and lever *O* are substantially the same as in the last case, except that for convenience these parts are preferably inverted. To the lever *O* is attached a spring, *S*, against the end of which an arm of the telephone-hook bears, as shown. On hanging up the instrument the spring *S* is pressed toward the lever until the tension of the spring overcomes the attraction at the armature, when the latter is suddenly withdrawn, generating the magneto impulse to actuate the signal.

From the description hereinbefore given of the construction of the automatic shunt mechanism its operation will be readily understood. It will be seen that while the apparatus is in its normal position the armature-coil is cut out of circuit, but is thrown into circuit at the beginning of the movement of the call mechanism by reason of the movement of the sleeve, and is maintained in circuit continuously until the automatic signaling impulse has been transmitted, and the disk and sleeve return to their normal position.

I have considered it unnecessary to illustrate or describe the conventional connections with the telephone and the line, as such are of the usual form and arrangement.

It will be seen that my invention involves no revolution of existing and well-known forms of magneto-calls, necessitating but a slight change and that one of addition only.

Having thus described my invention, what I claim, and desire to secure by Letters Patent, is—

1. In a magneto-call apparatus for telephone lines, the combination, with the telephone-supporting device and the mechanism for generating the magneto impulse, of means, substantially as described, whereby the act of replacing the telephone on its support shall, without volition to that end on the part of the user, cause said mechanism to generate a magneto impulse and notify the central office that the line is no longer in use, as set forth.

2. In combination with a magneto-call apparatus, means, substantially as described, for storing a reserve force by the act of making a call or answering one, which force, upon being brought into action, generates a magneto impulse, as and for the purpose set forth.

3. In combination with the armature of a magneto-call a spring arranged to be brought

and held under tension by the act of making a call, or answering one, and means, substantially as described, for releasing said spring by the replacing of the telephone, whereby the armature is given the necessary sudden movement and the magneto signaling impulse is generated, as set forth.

4. In a magneto-call apparatus, an armature, mechanism, substantially as described, for revolving the same through the medium of a force which is stored in the act of making or answering a call, and a telephone-supporting device adapted to arrest the movement of the revolving mechanism and to release the same when the instrument is replaced, whereby a magneto-signal is automatically transmitted, as set forth.

5. In a magneto-call apparatus, a crank-shaft for actuating the call, and independent actuating mechanism, substantially as described, normally in engagement with said shaft, which in the act of sending the call is thrown out of engagement with the shaft, but falls into engagement again and revolves the shaft and armature upon replacing the telephone, as set forth.

6. In a magneto-call apparatus, independent mechanism for actuating the armature substantially as described, whereby in the act of sending a call a reserve force is stored, in combination with a telephone-support adapted to arrest the movement of the parts active in storing said force and to release the same in the act of or incidental to replacing the telephone on its support, as set forth.

7. In combination with a magneto-call apparatus, a spring-actuated disk normally in engagement with the shaft for revolving the armature, which disk is carried in the act of sending the call and against the resistance of the spring, to a position in which its motion is arrested and its engagement with the armature-moving mechanism is suspended pending the making of the call, a stop, and releasing mechanism connected with the telephone-supporting device, substantially as described, whereby in the act of replacing the telephone on its support the disk is released, leaving the spring free to actuate the signal, as set forth.

8. In a magneto-call apparatus, a crank-shaft for actuating the call, a toothed wheel secured thereto, and a disk which supports a pawl normally in engagement with said wheel, whereby the shaft and disk are caused to revolve together, in combination with means for arresting the motion of the disk and for disengaging the pawl, and mechanism for automatically moving the stop and releasing the disk, as set forth.

9. In a magneto-call apparatus, a disk normally connected with the armature, in combination with the telephone-supporting device, constructed as described, whereby it is adapted to engage with the disk, the said supporting device being arranged to maintain engagement with said disk pending the removal of the telephone from its support, and only to

release it when the instrument is finally replaced, as set forth.

10. In a magneto-call apparatus for telephone-lines, mechanism, substantially as described, for automatically transmitting a signal by the release of a reserve force stored in the act of sending or answering a call, in combination with a shunt device constructed substantially as set forth, and adapted to cut out the armature-coil while the apparatus is in

its normal condition, to shunt it into circuit while the call is being made, and to retain the connections in circuit until the automatic signaling impulse has been transmitted, as and for the purpose set forth.

WILLIAM PAINTER.
